WALTER H. SMITH, OF WILKINSBURG, PENNSYLVANIA, ASSIGNOR TO WESTINGHOUSE ELECTRIC & MANUFACTURING COMPANY, A CORPORATION OF PENNSYLVANIA

CONTROL APPARATUS

Application filed May 12, 1927. Serial No. 130,701.

This invention relates generally to control apparatus and more particularly to a time element device for controlling the make and break of circuits.

- 5 The object of the invention, generally stated, is the provision of a time element device for controlling circuits that shall be simple and efficient in operation and readily and economically manufactured.
- 10 A more specific object of the invention is to provide for the stopping of a sequence switch or drum in predetermined positions to effect a step-by-step operation.

Another object of the invention is the provision of a circuit-controlling device, the operation of which will depend upon the operation of an air engine.

Other objects of the invention will, in part, be obvious, and will, in part appear herein-
20 after.

The invention accordingly is disclosed in the embodiment thereof shown in the accompanying drawings and comprises the structural features, the combination of elements, and arrangement of parts, that will be exemplified in the structure hereinafter set forth and the scope of the application of which will be indicated in the claims.

For a fuller understanding of the nature 30 and objects of the invention reference may be had to the following detailed description taken in conjunction with the accompanying drawings in which;

Figure 1 is a view in side elevation of a 35 circuit control device constructed in accordance with this invention,

Fig. 2 is a view partly in section and partly in side elevation showing features of the construction, and,

Fig. 3 is a diagram, showing the circuit controlling device associated with an air engine and connected in a simple circuit.

Referring now to the drawings and particularly to Fig. 3, the numeral 10 indicates generally a sequence drum disposed to be actuated by an air engine 11. As illustrated, a plurality of contact fingers 12, 13 and 14 are disposed to be engaged by the sequence drum 10 when it is rotated.

50 The air engine 11 may be of any well-

known type and comprises a plurality of cylinders 15 and 16 in which the pistons 17 and 18 are slidably mounted. In order to utilize the engine for actuating the sequence drum, a rack 19 is mounted between the pistons 17 and 18 and disposed to engage a pinion 20 which is mounted on the end of the sequence drum shaft 21.

The admission and exhaust of compressed air to and from the cylinders 15 and 16 respectively may be controlled by means of electromagnetic valves 22 and 23. As will be observed, the valves which may be of a type commonly used for controlling air engines are inverted relative to one another. Therefore, when both the valves are energized, compressed air will be admitted through one valve and exhausted through the other, as in this particular case, air will be admitted through valve 23 and exhausted through valve 22 and the pistons 17 and 18 will move to the right. If both the valves are deenergized, air will be exhausted through valve 23 and admitted through valve 22 and the pistons 17 and 18 will move to the left, while if valve 23 is energized and valve 22 deenergized, air will be admitted to both of the pistons and the engine will come to rest.

The supply of compressed air for actuating the air engine may be obtained from any suitable source such as a reservoir (not shown). The compressed air may be transferred to the air engine by means of air lines 24 and 25.

85 The novel features of this invention will now be described. In order to control the operation of the air engine, and the sequence drum, provision is made for periodically interrupting the energization of one of the valves of the air engine.

As shown, a resilient expandable container 26 which may be constructed in any suitable manner as, for example, from a length of sylphon tubing, is provided and a contactor 27 is disposed thereon in alignment with the contact fingers 28 and 29, which are connected in a circuit that will be referred to hereinafter.

80 The resilient container 26 is connected by 100

means of an air line 30 with the valve 23. As illustrated, an electromagnetic valve 31 and a diaphragm 32 having an orifice 33 is interposed in the air line to control the supply of compressed air to the container 26.

The electromagnetic valve 31 may be of any well-known construction such as is used in the control of air engines. In this particular embodiment of the invention the 10 valve 31 is disposed to admit compressed air to the container 26 when it is deenergized and to permit the exhaust of air from the container when energized.

In designing the exhaust port of the valve 15 31 it is made large as compared with the orifice 33 provided in the diaphragm 32. Accordingly, the air may be exhausted from the container 26 more quickly than it can be delivered through the orifice 33.

20 Therefore, in the operation of the device the air from the container 26 may be exhausted quickly so as to permit it to collapse and snap the contactor 27 out of engagement with the contact fingers 28 and 29. Such an 25 action is desirable when the device is utilized for interrupting electric circuits.

In this particular embodiment of the invention, a storage battery 34 is provided for supplying the electrical energy required for 30 energizing the electromagnetic valves 22, 23 and 31. However, it will be readily understood that any other suitable source of electrical energy available in installations where this invention is provided may be utilized.

35 Assuming that it is desired to actuate the sequence drum 10 which may be provided with any number of contact segments for controlling any electrical control system, then the manually-operable switch 35 is 40 closed, and an energizing circuit for the valve 23 is established. Current now flows from the battery 34 through conductor 36, the actuating coil of valve 23, conductor 37, back to the negative side of the battery. The exhaust 45 port of valve 23 is immediately closed and communication is established between the air line 25 and the cylinder 15. When the valve 23 is opened compressed air flows from the air line 25 through the air line 30, orifice 50 33, valve 31, to the container 26. The valve 22 remains deenergized until the container 26 is expanded to project the contactor 27 into engagement with the contact fingers 28 and 29.

55 Air pressure is now applied to the piston 18 but since the valve 22 is also open, the cylinder 15 is connected to the air line 24 and the piston 17 is subjected to a predetermined air pressure. Consequently the air 60 engine is in a balanced condition and no movement of the pistons results from the energization of the valve 23.

When the contactor 27 is projected into engagement with the contact fingers 28 and 65 29, an energizing circuit for the valve 22

is established which may be traced from the battery 34 through conductor 36, contact fingers 12 and 13 bridged by the contact segment 38 of the drum 10, conductor 39, contact fingers 29 and 28 bridged by the contactor 27, conductor 40, the actuating coil of the valve 22, conductor 37 back to the negative side of the battery.

Upon the actuation of the valve 22 to its closed position, the supply of compressed air to the cylinder 15 is interrupted and the latter is connected to the exhaust port of the valve. Since only the piston 18 is subjected to an air pressure, the pistons move to the right and the sequence drum 10 through the operation of the rack 19 and pinion 20 is rotated to the left.

As will be noted, the contact segment 38 is provided with depending members disposed to engage the contact finger 14. As 85 the drum rotates, the first depending member engages the contact finger 14 and an energizing circuit for the valve 31 is established which may be traced from the battery 34, through conductor 36, contact fingers 12 90 and 14 bridged by the contact segment 38, conductor 41, the actuating coil of the valve 31, and conductor 42 back to the negative side of the battery. Upon the energization of the valve 31, air is exhausted from the container 26 and it collapses and snaps the contactor 27 95 out of engagement with the contact fingers 28 and 29.

The energizing circuit of the valve 22 is interrupted and a balanced condition in the air 100 engine re-established in a manner described hereinbefore. However, in designing the sequence drum and the air engine, provision is made whereby the sequence drum will be rotated far enough to carrying the depending 105 members of the contact segment 38 beyond the contact finger 14 before the air engine is stopped by the energizing circuit of valve 22.

The sequence drum will stop at a predetermined point and will not advance again until sufficient compressed air has flowed into the 110 container 26 to expand it and project the contactor 27 into engagement with the contact fingers 28 and 29 re-establishing the energizing circuit of the valve 22. It will be readily 115 understood that by varying the size of the orifice in the diaphragm 33, provision may be made for any desired time element between the disengagement of the contactor 27 from the contact fingers 28 and 29 to interrupt the 120 energizing circuit of the valve 22 and the re-establishment of the valve circuit to continue the operation of the air engine.

From the foregoing description, the operation 125 of the device will be readily understood. However, Fig. 3 only diagrammatically illustrates the invention. Accordingly, reference is now made to Figs. 1 and 2 which illustrate an embodiment of the invention suitable for manufacture.

As illustrated in Fig. 2, a base plate 43 having two laterally extending brackets 44 and 45 is provided. The collapsible container or sylphon tube 26 is disposed between the brackets, the upper end being fixed to the bracket 45, in any suitable manner, while the low end is free to move. Depending from the lower end of the container 26 is a rod 46, which extends through the bracket 44 and has attached to its upper end a head 47 made from some insulating material.

As shown, the head 47 is disposed in alignment with two resilient contact plates 48 and 49 carried by the base plate 43 and insulated therefrom in any suitable manner common in the art. It will be observed that the plates 48 and 49 are so mounted that they do not engage with one another until actuated by the downward movement of the head 47.

The valve 31 is also supported on the base plate 43 being cast integral with the upper part thereof. As shown, the valve 31 comprises an electromagnet 50 and a valve stem 51 disposed to be operated by the former. In order to provide for the actuation of the valve, an armature 52 is mounted on the valve stem and so arranged that when it is actuated upon the energization of the electromagnet, the valve is projected downwardly to establish communication between the container 26 and the exhaust port 53, and to interrupt communication between the air line 30 and the container 26.

As will be observed, ducts 54 and 55 are provided in the upper part of the casting for establishing communication between the air line 30 and the container 26, and between the exhaust port 53 and the container 26. A removable cap 56 is provided to give access to the chamber 57 in which the removable valve seats 58 and 59 are mounted. Further, in order to provide for the actuation of the valve manually, the valve stem 51 is extended through the armature and a button 60 is provided for operating it.

In the operation of the device illustrated in Fig. 2, prior to the energization of the magnet 50, air may flow from the air line 30, through the duct 54, valve 31, duct 55 to the container 26. Upon the expansion of the container, the rod 46 and head 47 are projected downwardly and the contact plate 48 is moved into engagement with the contact plate 49. Since both of the plates are made from some resilient material they will not be damaged by the overtravel of the rod 46.

Upon the energization of the magnet 50 the armature 52 is raised and the valve 31 is moved to its uppermost position, interrupting communication between the air line 30 and the container 26. Further, communication is established from the container 26 through duct 58, valve 51 to the exhaust port 53. By making the exhaust port of suitable size, pro-

vision may be made for exhausting the air from the container at any desired rate.

A plurality of openings 61 are provided in the base plate 43 so that the device may be mounted on any support by means of bolts or the like.

Since certain changes may be made in the above construction and different embodiments of the invention may be made without departing from the spirit and scope thereof, it is intended that all matter contained in the above description or shown in the accompanying drawings shall be interpreted as illustrative and not in a limiting sense.

I claim as my invention:

1. In control apparatus, in combination, a sequence switch, an air engine provided with valves disposed to operate the sequence switch, circuits for controlling the operation of the valves, one of said circuits being controlled by the sequence switch, a switch biased to an open position and adapted to be actuated by air pressure disposed to control the other valve circuit, means for conveying compressed air to the pressure-actuated switch when the valve controlled by the sequence switch is open, and means for periodically releasing the pressure applied to the switch to permit it to open.

2. In control apparatus, in combination, a sequence switch, an air engine provided with valves disposed to operate the sequence switch, circuits for controlling the operation of the valves, one of said circuits being controlled by the sequence switch, a switch biased to an open position and adapted to be actuated by air pressure disposed to control the other valve circuit, means for conveying compressed air to the pressure actuated switch when the valve controlled by the sequence switch is open, means for periodically releasing the pressure applied to the switch to permit it to open, said pressure-releasing means being adapted to release the pressure quickly enough to permit substantially a snap action of the switch.

3. In control apparatus, in combination, a sequence switch, an air engine provided with valves disposed to operate the sequence switch, circuits for controlling the operation of the valves, one of said circuits being controlled by the sequence switch, a switch biased to an open position and adapted to be actuated by air pressure disposed to control the other valve circuit, means for conveying compressed air to the pressure-actuated switch when the valve controlled by the sequence switch is open, and means for periodically releasing the pressure applied to the switch to permit it to open, said air-conveying means being provided with a constricted opening to delay for a predetermined period the actuation of the pressure-operated switch to its circuit-closing position.

4. In control apparatus, in combination, a

sequence switch, an air engine provided with valves disposed to operate the sequence switch, circuits for controlling the operation of the valves, one of said circuits being controlled by the sequence switch, an air-pressure-actuated switch biased to an open position, and disposed to control the other valve circuit, means for conveying compressed air to the pressure-actuated switch when the valve controlled by the sequence switch is open, means for periodically releasing the pressure applied to the switch to permit it to open, said means for conveying compressed air being provided with a constricted opening to delay for a predetermined interval the operation of the switch after the closure of said pressure-releasing means, said pressure-releasing means being adapted to release the air pressure quickly to effect a quick opening of the pressure actuated switch.

In testimony whereof, I have hereunto subscribed my name this 2nd day of May, 1927.

WALTER H. SMITH.
